CLAIM

The ornamental design for an aqueous ozone generator cartridge, substantially as shown and described.

DESCRIPTION

FIG. 1 is a front isometric view of the new design; FIG. 2 is a rear isometric view of the design of FIG. 1; FIG. 3 is a right side view of the design of FIG. 1; FIG. 4 is a front view of the design of FIG. 1; FIG. 5 is a back view of the design of FIG. 1; and, FIG. 6 is a top view of the design of FIG. 1.

The design consists of the features of shape, ornamentation, and configuration of the article as shown in the drawings. The broken lines shown in the drawing are for the purpose of illustrating portions of the article that form no part of the claimed design. The left side view is a mirror image of the right side view of FIG. 3 and is therefore omitted. The bottom view is a mirror image of the top view of FIG. 6 and is therefore omitted.
